CLAIM

The ornamental design for a prisoner transport module, as shown and described.

DESCRIPTION

FIG. 1 is a rear perspective view of a prisoner transport module showing my new design;
FIG. 2 is a front perspective view thereof;
FIG. 3 is a top plan view thereof;
FIG. 4 is a right side elevational view thereof, with the left side being a mirror image thereof;
FIG. 5 is a front elevational view thereof;
FIG. 6 is a rear elevational view thereof; and,
FIG. 7 is a rear elevational view of a second embodiment, the only difference being the single door.
